UNITED STATES PATENT OFFICE.

JOHN B. ROHRER, OF PHILADELPHIA, PENNSYLVANIA, ASSIGNOR TO
SAMUEL COOPER AND JOHN HALL, OF SAME PLACE.

DESIGN FOR A LOUNGE.

Specification forming part of Design No. 6,507, dated March 18, 1873.

To all whom it may concern:

Be it known that I, JOHN B. ROHRER, of Philadelphia, Pennsylvania, have invented a Design for a Lounge, of which the following is a specification:

The nature of my design is fully illustrated by the accompanying drawing, in which the diagrams, Figures 1 and 2, represent the outline of the back and end of the body of the lounge, and Fig. 3 a perspective view of the complete lounge.

The outline of the back of the lounge is of the general shape shown by the diagram, Fig. 1, this being slightly varied, as desired, by minor ornamentation, as in Fig. 3, where the angularity is broken by scroll-like carving, &c. The end A is of the rounded form shown in Figs. 2 and 3. The front molding B of the

lounge is overlapped by the curved molding B' of the arm, instead of merging into the same as usual, and both of the said moldings, as well as that at the back of the lounge, are elaborately ornamented by carving, as shown.

I claim—

1. The design for the outline of the back of a lounge, substantially as shown in Fig. 1.
2. The design for the whole lounge, as represented in Fig. 3.

In testimony whereof I have signed my name to this specification in the presence of two subscribing witnesses.

JOHN B. ROHRER.
